UNITED STATES PATENT OFFICE

153,259

DESIGN FOR A SHOE OR SIMILAR ARTICLE

Walter Braun, Los Angeles, Calif.

Application June 18, 1948, Serial No. 147,059

Term of patent 7 years

(Cl. D7—7)

To all whom it may concern:

Be it known that I, Walter Braun, a citizen of the United States, residing in Los Angeles, in the county of Los Angeles, State of California, have invented a new, original, and ornamental Design for a Shoe or Similar Article, of which the following is a specification, reference being had to the accompanying drawing, forming a part thereof.

The essential feature of my design is the upturned snap toe with seam turned in.

I claim:

The ornamental design for a shoe or similar article, as shown and described.

WALTER BRAUN.
